Primary Examiner—T. Chase Nelson*Assistant Examiner*—John Windmuller(74) *Attorney, Agent, or Firm*—Rosenberg, Klein & Lee(57) **CLAIM**

The ornamental design for a housing of antenna device, as shown and described.

DESCRIPTION

FIG. 1 is a perspective view of a housing of antenna device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom side elevational view thereof;

FIG. 7 is a top side elevational view thereof; and,

FIG. 8 is another perspective view of a housing of antenna device of the invention.

The broken lines in the Figures are for illustrative purposes only and form no part of the claimed design.
